(57) **CLAIM**

The ornamental design for a power adapter for electronic devices, as shown and described.

DESCRIPTION

FIG. 1 is a perspective view of a power adapter for electronic devices, showing the new design.

FIG. 2 is a side view of the power adapter of FIG. 1, the opposite side being a mirror image thereof.

FIG. 3 is a top view of the power adapter of FIG. 1.

FIG. 4 is a bottom view of the power adapter of FIG. 1.

FIG. 5 is a first end view of the power adapter of FIG. 1.

FIG. 6 is a second end view of the power adapter of FIG. 1; and,

FIG. 7 is a cross-sectional view of the power adapter of FIG. 1, taken at section 7-7 of FIG. 6.

The broken lines shown represent the portions of the power adapter for electronic devices that form no part of claimed design.
